ELECTRIC ALARM CLOCK

René Esselin, Lyon, France, assignor to Etablissements Esselin & Cie (Societe a responsabilite limitee), Lyon, Rhone, France

Application January 11, 1950, Serial No. 7,171
In France September 19, 1949

Term of patent 7 years

(Cl. D42—7)

To all whom it may concern:

Be it known that I, René Esselin, a French citizen, residing at Lyon, France, have invented a new, original, and ornamental Design for an Electric Alarm Clock, of which the following is a specification, reference being had to the accompanying drawing, forming a part thereof.

The figure is a front perspective view of an electric alarm clock, showing my design.

I claim:

The ornamental design for an electric alarm clock, as shown.

RENÉ ESSELIN.
